WRITING INSTRUMENT

Hans Reinhard Fehling, Zug, Switzerland, and Alfred Dennis Street, Pinner, England, assignors to I.R.C. Limited, London, England, a company of Great Britain

Filed Mar. 6, 1963, Ser. No. 73,848

Term of patent 14 years

(Cl. D74—17)

FIG. 1 is a side view of a writing instrument showing our new design, the side opposite thereto being a mirror image thereof; and

FIG. 2 is a top view thereof.

We claim:

The ornamental design for a writing instrument, as shown and described.
